UNITED STATES PATENT OFFICE.

MELVIN A. LURAAS, OF EAU CLAIRE, WISCONSIN.

RAIL-JOINT.

1,122,520.

Specification of Letters Patent. Patented Dec. 29, 1914.

Application filed June 7, 1913. Serial No. 772,366.

To all whom it may concern:

Be it known that I, MELVIN A. LURAAS, a citizen of the United States, residing at Eau Claire, in the county of Eau Claire and State of Wisconsin, have invented certain new and useful Improvements in Rail-Joints, of which the following is a specification.

This invention relates to a novel method 10 of strengthening the joints of rail splices of railroads to afford a reliable means whereby the joint or splice is supported and rendered as strong and rigid as any other part of the rail; and it consists of truss-rods of peculiar 15 form in connection with a specially designed fish plate to be hereinafter fully described.

In the present state of the art, it has been found impossible in the operation of railroads to prevent low joints, or an injurious 20 depression of the rail line at each splice of the rails, which are in sections of suitable length for convenient use.

At each joint a small space is left between the ends of the two adjoining rails to permit 25 expansion longitudinally. When the wheels of a car roll along the rails and over these splices, they produce a pounding effect upon the rail ends gradually flattening the tops of the rails at these points and doing 30 irreparable damage to the rail, the life of which is greatly lessened on that account; besides much damage is done also to the rolling equipment on account of the incessant jarring.

The primary object of the invention is to obviate the above and various other objectionable features and to provide a rail joint 35 that is readily adjustable vertically to maintain an even surface on top; to provide for a distribution of the load or unequal effect 40 of the load at the joint due to the wheels passing across the expansion-space from one rail to another, so that the rails, well toward the center, will receive the major portion 45 of the strain; to prevent the slight alternating vertical motion of the ends of the rails at the joints thereof, which otherwise assist in the flattening of the top of the rails at the ends; and to reduce the vertical 50 vibratory movement of the rails to a material extent.

The above and additional objects are accomplished by such means as are illustrated in their preferred embodiment in the accompanying drawings, described in the following specification and then more particularly

pointed out in the appended claims forming a part of this application.

In describing the invention in detail, reference will be had to the accompanying 60 drawings, wherein like characters denote like or corresponding parts throughout the several views and in which;

Figure 1 is a perspective view illustrating the application of the invention; Fig. 2 is 65 a longitudinal sectional view of the rail splice, the rail being shown in elevation; Fig. 3 is a section on the line 3—3 of Fig. 2; Fig. 4 is a section on the line 4—4 of Fig. 2; Fig. 5 is a detail perspective view of the 70 locking pin or member, and Fig. 6 is a detail perspective view of the lifting jack.

Referring now to the drawings, wherein is illustrated the preferred form of my invention, the numeral 1 designates a railway rail 75 of ordinary construction over which a specially designed fish plate designated in its entirety by the numeral 2 is adapted to be arranged, the said plate being disposed at the meeting or adjoining ends of the rails where 80 it is bolted through the medium of bolts 3 extending transversely through the fish plate and the web of the rails. The plate 2 comprises a rail engaging portion 4 through which the bolts 3 extend and a base portion 85 5 adapted to engage the base of the rail 1, the extremities of the fish plate having enlargements 6 depending therefrom adapted to overlap the base of the rail and extend beneath the under face thereof, the inner faces 90 of the said enlargements being arranged in spaced relation for a purpose to be herein-after fully described. The central portion of the fish plate 2 is provided with an extension 7 adapted to overlap the base of the 95 rail 1 and extend therebeneath, so as to project beyond the opposite edge thereof, as is clearly shown in Fig. 3 of the drawings, the said extension being disposed directly beneath the meeting ends of the rail. A lift- 100 ing jack, designated in its entirety by the numeral 8 is arranged beneath the extension 7 of the fish plate, the jack comprising a body portion 9 having an annular flange or enlargement 10 formed integrally with and 105 at the top thereof, the said enlargement having a plurality of cut out portions or recesses 11 formed therein, so as to extend or radiate toward the periphery of the flange from an enlargement 12 formed in axial 110 alinement with the body portion 9. The enlargement 12 is provided with a pin 13

formed integrally therewith adapted to fit within an opening or aperture 14 formed within the extension 7 of the fish plate.

A screw member 15 having an exteriorly threaded shank 16 projecting from its upper extremity is adapted to fit within a recess 17 formed within the body portion 9 of the lifting jack, and the rotation of the said body is adapted to force the enlargement 12 of the jack firmly into engagement with the under face of the extension 7, the enlargement 13 engaging the under face of the rails. A rotation of the body 9 will force the extension 7 firmly against the under face of the rails 1 to support the meeting ends thereof in rigid and alined relation.

After adjusting the body as desired, a locking pin or member 19 is adapted to be inserted through an opening 20 formed within the projecting edge of the extension 7, the said member fitting within one of the recesses 11 of the enlargement 10 of the lifting jack and preventing a reverse rotation of the jack beneath the rail. To lock the said member within the opening 20 provided therefor after fitting the same within one of the recesses 11, the flattened portion 21 thereof is bent to overlap the edge of the extension 7 as is clearly shown in Fig. 2 of the drawings, this bending of the member preventing accidental vertical movement thereof.

A truss-rod 22 is adapted to be arranged over the lower extremity of the screw member 15, the said rod fitting within a bifurcation 23 formed within the said member and extending at an angle therefrom to and between the enlargement 6 of the fish plate where it is permanently secured through the medium of bolts 24 extending transversely through the said enlargement and through the extremities of the rod 22.

It will be seen from the above, taken in connection with the accompanying drawings that the two meeting ends of the rail are held tightly together and locked in such a position by reason of the truss-rod 22 disposed within the bifurcation of the screw member 15; that the tightening of the lifting jack 9 beneath the extension 7 of the fish plate will support the meeting ends of the rail in perfect alinement, the locking member 19 and the truss-rod 22 preventing a reverse rotation of the said lifting jack 9 or screw member 15; and that minute vertical adjustment of the meeting ends of the rail may be accomplished by the manipulation of the body 9, such adjustment being rendered permanent by inserting the pin 19 within one of the recesses 11 of the lifting jack.

In reduction to practice, I have found that the form of my invention, illustrated in the drawings and referred to in the above description, as the preferred embodiment, is

the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent is:

1. In a railway rail joint, the combination of a fish plate, an extension formed integrally therewith adapted to engage the base of the rail beneath the meeting ends thereof, a lifting jack having a plurality of recesses formed therein, the said jack adapted to engage the under face of the said extension, and means including a removable pin adapted to pass through the said extension and within one of the said recesses for locking the said jack against reverse rotation, as and for the purpose set forth. 75

2. In a railway rail joint, the combination of a fish plate, an extension formed integrally with the said plate adapted to extend beneath the rail base for supporting the meeting ends of the rails, enlargements formed integrally with the said fish plate at the extremities thereof, the said enlargements adapted to overlap the rail base and extend therebeneath, a lifting jack adapted to engage the under face of the said extension for supporting the same in engagement with the base of the rail, and means including a truss-rod carried by the said enlargements and engaging the said lifting jack for locking the latter against reverse rotation, as and for the purpose set forth. 80

3. In a rail joint, the combination of a fish plate, an extension formed integrally therewith adapted to pass beneath the base of the rails for supporting the meeting ends thereof, enlargements formed integrally with the said fish plate adapted to overlap the rail base and extend therebeneath, a lifting jack including a body portion adapted to support the said extension, the said body portion having a plurality of recesses formed therein, means carried by the said extension adapted to engage one of the said recesses for locking the jack against reverse rotation, a screw member projecting from the said jack for vertically adjusting the same, and means including truss-rods carried by the said enlargements and engaging the said screw member for locking the latter against reverse rotation, as and for the purpose set forth. 85

4. In a railway rail joint, the combination of a fish plate, an extension formed integrally therewith adapted to overlap the base of the rails and extend beneath the meeting ends thereof, enlargements formed inte- 90

- grally with and upon the extremities of the fish plate adapted to overlap the rail base and extend therebeneath, a lifting jack including a head portion adapted to engage 5 the under face of the said extension for supporting the same in firm engagement with the base of the rail, the said body portion of the jack having a plurality of recesses formed therein, an extension formed integrally with the said body portion adapted to fit within an opening formed within the said extension of the fish-plate, a removable locking member adapted to be inserted within an opening formed within the said extension for engagement with one of the said recesses for locking the jack against reverse rotation, a screw member for operating the said jack, the said member having a bifurcated lower end, and means including a 15 truss-rod secured to the said enlargements and fitting within the said bifurcated end of the screw member for locking the latter against reverse rotation, as and for the purpose set forth.
- 20 5. A rail joint including a fish-plate, a portion of which is adapted to extend beneath the meeting ends of the rails, a lifting jack disposed beneath the extended portion of the fish-plate, and means engaging said fish-plate and said jack to maintain the latter in adjusted position, as and for the purpose set forth.
- 25 6. A rail joint comprising a fish-plate, an extension formed thereupon, said extension
- adapted to be disposed beneath the meeting ends of the rails, a lifting jack disposed beneath said extension, means formed integrally with said lifting jack adapted to extend through said fish-plate extension, and means engaging said fish-plate extension and 40 said lifting jack to maintain the latter in the desired adjusted position, as and for the purpose set forth.
7. In a rail joint, a fish-plate having an extension formed integrally therewith, said extension adapted to be disposed beneath the meeting ends of the rails, said extension being provided with an opening, a lifting jack disposed beneath said extension, a projection formed integrally with said jack 45 50 adapted to fit said extension opening, a screw rod disposed for engagement with said jack, a truss-rod connected to the said fish-plate and engaged by said screw rod, the rotation of the said lifting jack adapted to actuate said screw rod to force the same against said truss-rod and the said projection into said opening, and means engaging the said fish-plate extension and the said lifting jack to maintain the latter in the desired adjusted position, as and for the purpose set forth.
- 55 60 In testimony whereof I affix my signature in presence of two witnesses.

MELVIN A. LURAAS.
